UNITED STATES PATENT OFFICE.

EMIL EBERHARDT, OF STETTIN, GERMANY.

FIRE-TUBE BOILER.

No. 808,353.

Specification of Letters Patent.

Patented Dec. 26, 1905.

Application filed April 18, 1905. Serial No. 256,255.

To all whom it may concern:

Be it known that I, EMIL EBERHARDT, engineer, of No. 5 Grabowerstrasse, Stettin, Germany, have invented new and useful Improvements in Fire-Tube Boilers, of which the following is a specification.

My invention has for its object the construction of a fire-tube boiler in which one or more smoke-consuming chambers having adjoining water-spaces on several sides are arranged between the fire-chamber and the fire-tubes.

A further object of my invention is to provide a fire-tube boiler which will be simple in construction and economical in operation. In boilers of this class at present in use it is found that it is difficult to secure a complete combustion of the furnace-gases without increasing the consumption of fuel to a great extent.

By reason of the novel construction of my improved boiler, which will hereinafter be fully explained, I am enabled to obtain a complete combustion of the furnace-gases, and thereby obtain a greater heating power with a given amount of fuel than is secured by former devices of this character.

The essential feature of my invention is the arrangement of the smoke-consuming chamber or chambers between the smoke-box and the chamber in the water-space of the boiler, the smoke-consuming chambers being provided with an air-pipe passing through the smoke-box.

In the accompanying drawings, forming part of this specification, Figure 1 is a transverse section of my improved boiler. Fig. 2 is a section through the line C D of Fig. 1. Fig. 3 is a section through the line A B of Fig. 1. Fig. 4 is a longitudinal vertical section on the line G H of Fig. 2, showing form of smoke-box. Figs. 5 and 6 are respectively a section through the line E F of Fig. 4 and a plan view of the smoke-box.

I will now proceed to describe my invention with reference to the drawings and then more particularly point out the distinctive features of my apparatus in the following claims.

My apparatus comprises the usual shell or casing and is provided with fire-chambers *e e'*, which are arranged in the two lower flame-tubes. Above these tubes is a smoke-consuming tube *a*, which is connected with the fire-chambers by the smoke-box *b*, (shown in

Figs. 4 and 6,) while the fire-tubes *o*, arranged on both sides of the smoke-consumption chamber *a*, are connected therewith by a passage *f*. The other ends of the fire-tubes communicate with the chimney *p*, arranged above the smoke-box. The smoke-box *b* is lined with fire-brick or other similar material *r*.

In the outer wall of the smoke-box *b* I provide one or more openings *l* for the admission of air, the width of which may be varied by means of dampers *d*.

Formed by the walls *m* and *n* of the smoke-box is a chamber *h* for the preliminary heating of the air. *k* represents walls or partitions arranged within the chamber *h* formed by the walls *m* and *n* of the smoke-box *b* whereby the fresh air upon entering the openings *l* is forced over the surface of the smoke-box in proximity to the fire before passing out of the nozzle-pipe *c* into the smoke-consuming passage. The pipe *c* is not lined with fire-brick or other restraining material, and thus the furnace-gases passing over it unimpeded are heated to an intense degree.

When the boiler is heated, the furnace-gases, following the course above described, exercise a suctional action on the nozzle-pipe *c*, whereby the air entering through the openings *l* is drawn into the double chamber of smoke-box *b*. As the air passes about the partitions *k* and into the nozzle-pipe *c* it is intensely heated, and complete combustion of the furnace-gases is effected.

Having thus described my invention, what I claim as new, and desire to secure by Letters Patent, is—

1. In a boiler, the combination of a shell, fire-chambers therein, a smoke-consumption chamber arranged above said fire-chambers, a smoke-box connecting said fire-chambers and said smoke-consumption chamber, fire tubes partly surrounding and communicating with said smoke-consumption chamber, a chimney mounted above said smoke-box and connected to said fire-tubes; an air-chamber formed by the walls of said smoke-box and communicating with said smoke-consuming chamber, air-admission ports in said air-chamber, and partitions arranged within said air-chamber for directing the course of the air admitted through said ports.

2. In a boiler, the combination of a shell, fire-chambers therein, a smoke-consumption

chamber arranged above said fire-chambers, a smoke-box connecting said fire-chambers and smoke-consumption chamber, fire-tubes partly surrounding and communicating with 5 said smoke-consumption chamber, a chimney mounted above said smoke-box and connected to said fire-tubes; an air-chamber formed by the walls of said smoke-box and communicating with said smoke-consuming 10 chamber air-admission ports communicating with said air-chamber and provided with dampers for regulating the admission of air thereto, and directing-walls within said air-chamber for directing the course of the air 15 admitted through said openings.

3. In a boiler, the combination of a shell, fire-chambers therein, a smoke-consumption chamber arranged above said fire-chambers, fire-tubes partly surrounding said smoke- 20 consumption chamber and communicating therewith, a smoke-box, a chimney mounted above said smoke-box and communicating with said fire-tubes; an air-chamber formed by the walls of said smoke-box, and a nozzle

connection between said air-chamber and 25 smoke-consumption chamber.

4. In a boiler, the combination of a shell, fire-chambers therein; a smoke-consumption chamber arranged above said fire-chamber, a smoke-box, fire-tubes partly surrounding 30 said smoke-consumption chamber and communicating therewith, a chimney mounted above said smoke-box and communicating with said heating-pipes; an air-chamber formed by the walls of said smoke-box, a nozzle connection between said air-chamber and said smoke-consumption chamber air-admission ports in said air-chamber provided with 35 dampers for regulating the admission of air, and directing-walls within said air-chamber 40 for directing the course of the air admitted through said openings.

In witness whereof I have signed this specification in presence of two witnesses.

EMIL EBERHARDT.
